AMUSEMENT DEVICE, REPRESENTING A
BUCKING BRONCHO

John J. Carniol, Stapleton, N. Y.

Application July 2, 1932, Serial No. 620,715

16 Claims. (Cl. 104—60)

This invention relates to amusement devices, adapted to be exhibited in amusement parks, or the like, and particularly to one, in which a number of mechanically operated artificial horses, carrying visitors, move independently of each other, over the same or separate tracks, and are capable of a number of momentary and irregular motions, besides those imitating the regular trotting motions of a mount.

10 One object of my invention therefore, is to provide amusement to the visiting public.

Another object is to produce in riders a sensation similar to that experienced by cow-boys "breaking" wild horses or bronchos, and the device is therefore properly named the: "Mechanical bucking broncho."

15 A third object is to provide an improved tractor for the horse, operating while being hidden from view, so as to produce the illusion of the artificial horse executing its various motions spontaneously.

20 A fourth object is to provide a tractor, which is adapted to be driven by any motive power in common use for similar purposes, for instance, electricity, be it by an electric motor, actuated from a third rail, or by storage batteries mounted on the tractor, or by a gasoline motor, or by a cable drive, etc.

25 A fifth object is to provide a mechanism on this tractor, which will produce the various motions, and irregular performances of the horse, automatically, and in sufficient variety.

30 A sixth object, in connection with the last named, is to make said mechanism of such construction, that the resulting motions will imitate the natural behavior of a live horse, as closely as possible, especially copy the relative movements of legs, body and head.

35 A seventh object, subservient to the last named, is to provide means, whereby the rocking motions of the body and the head, as well as the alternating movements of the legs of the horse, are imitated while in regular trotting action.

40 An eighth object is to provide means whereby the mechanical horse is actuated to imitate the sudden prancing motions of a broncho, more particularly those of rearing on the hindlegs or "taking head", secondly those of kicking up his heels and thirdly those commonly called "bucking", which in the present case are imitated by a close succession or combination of the first two "stunts", either in the order named or in reversed order.

45 A ninth object is to make these various sensations

5 tional actions of the mechanical horse foolproof, so that the device is safe enough even for children to use and to enjoy.

A tenth object, concurrent with the last named, is to provide means whereby the starting of the ride is made gradual—in case that the tractor is driven by electricity—, so that neither the rider nor the electric motor is endangered by a sudden jerky application of the motive power.

10 An eleventh object, contributing to the safety of the device, is to provide means whereby the rider can start or stop the movement of the horse at will.

15 A further object is to make the motions of the individual horses, as well as their installation, independent of each other, so that not only the operating mechanism of each horse is self-contained, but that also the tracks of the different horses can cross each other, if so desired.

20 Other objects and many of the attendant advantages of the invention will be apparent to persons skilled in the art to which the invention relates, as the same becomes better understood from the following detailed description, taken in connection with the accompanying drawings wherein one practical and preferred embodiment of the invention is illustrated and in which:

25 Figure 1 is the side elevation of a mechanical horse, built according to the invention, in a regular trotting position. It is to be understood that the lower part of the figure is hidden underground, in a trench, beneath the line A—A, as indicated. The alternate position of the horse and its extremities, are indicated by dotted lines.

30 Figure 2 is a front elevation of the horse and the tractor, the trench being indicated in section.

35 Figure 3 is a detailed side elevation of the carriage and its mechanism, on an enlarged scale, compared with that of Figure 1.

40 Figure 4 is a top view of the tractor, or carriage, on which the horse is mounted.

45 Figure 5 is a cross section of the horse in a rearing position, the tractor below ground being indicated only diagrammatically.

50 Figure 6 shows the horse in elevation, in a kicking position.

55 Figure 7 is a top view of the lever work of the inside mechanism of the horse, the latter being indicated in outlines only.

Figure 8 is a diagram, showing the shape of the controlling cam, and illustrating the se-

quence of the different stunt movements of the horse.

Figure 9 shows the arrangement of the conductor rail, and the subcontact shoe of the 5 motor.

Figure 10 is the wiring diagram.

The artificial horse itself is made of a substantially hollow body, that is: the trunk, the thighs, the shoulders and the neck must have 10 cavities in which the leverwork, directly governing the motions, can be installed with freedom to move; whether the rest of the body is hollow, is of no consequence, except for the saving of deadweight material. The outside can be covered with fur, and the apertures necessitated by certain joints, for instance at the chest, can be camouflaged by overlapping or folded skin; or the outer appearance of the horse and his harness may be represented in any suitable way. 15

20 The belly side of the horse is slotted sufficiently to permit the free movement of the supporting post 30 and the crank bar 31, actuating the balancer 32. The latter is a cross-beam on which the body is mounted. It is pivoted in its center, 33, on the supporting post, and when the horse is at rest, it is held in horizontal position.—While the horse moves forward in a regular trotting motion, the balancer continuously oscillates through a small angle, as shown in Fig. 1, but when it tilts forward or backward about 30 degrees, the horse seems to kick out its hind legs, or to rear upwardly on them, respectively.

25

The balancer, 32, is provided on its extremities with two rigid depending arms, 34 and 35, reaching down to the points where the shoulder joints or the thigh joints respectively are pivoted, designated by numerals 36 and 37. At these points the upper parts of the legs are pivoted upon a horizontal cross-shaft in such a way that they can be moved independently, of each other. This, as Figures 5 and 7 show for both hind and front legs, is accomplished by forming these shafts of two telescoped members, a solid shaft 36a and 37a respectively and a hollow shaft or sleeve, 36b and 37b, rotatably mounted thereon. Neither of these shafts quite reaches to the other end of the shaft it engages with, and with their outer extremities they are 40 fixedly mounted in the outer cover of the shoulder portion or the hip portion, respectively.

The disposition of the hollow shafts over the solid shafts is, as Figure 7 shows, for both legs made so that the hollow shafts are both on one side of the horse, for instance on the left side, so that then the right side legs are controlled by the solid shafts, fixedly jointed thereto, while the left side legs are fixedly jointed to the hollow shafts.

45 The movable cover of these joints is, at least along its upper periphery, made circular, as Figures 1 and 5 indicate, comprising at least a semicircle, and this semicircular joint is connected to the trunk portion by a segmental ball race, 43a, and 43b, or by any other antifrictional bearing device.

50 On the sleeve or hollow shaft of the front legs, as well as on the solid shaft of the hindlegs, are fixedly mounted two lever arms, extending in an upward and inward direction, i. e. 38 for the left front leg, and 39 for the right hind leg; and on the front solid shaft as well as on the hind hollow shaft are fixedly mounted two other lever arms, 40 and 41, extending in a downward and inward direction, the first one for the right

front leg and the latter for the left hind leg. These two pairs of levers are separately connected to two other pairs of levers, 38a and 40a for the front, and 39a and 41a for the rear, so as to form double toggle joints. The inner ends of these toggles are coupled together by a short cross piece, 42, and a little reflection, and observation, will reveal that when the cross piece, 42, is horizontally moved to and fro, the front toggle-joint will open, while the rear toggle 10 begins to close, and vice versa.

The same effect is obtained if instead the cross piece 42 is held rigidly in place, in relation to the center post, 30, and the balancer is 15 swung up and down.

Also, it will be evident from the way the upper parts of the shoulders and thighs are fixedly mounted in relation to the levers above described, that the legs will move forward and backward in synchronism with the motions of the toggle joints and imitate a horse's gait, namely: the left front leg and the right rear leg move simultaneously forward, while the right front leg and the left rear leg move backward. This relative motion, combined with the general advance 20 movement of the tractor on which the horse is mounted, gives the illusion of a trotting horse. The forward speed of the arc in which the legs swing, is not proposed to be excessive, as a prancing wild horse or broncho is more intent 25 on throwing his rider than on covering distance.

The angle in which the balancer oscillates is chosen so that alternately the front or the rear legs touch the ground. Evidently when the horse rears or kicks, the angle of oscillation 30 becomes greater and if either pair of legs is just to stay on, or to touch the ground, the center part of the horse must rise at the same time. Accordingly the stunt motions of the horse are combinations of mechanical means 35 which effect a momentary rise of the supporting post, 30, with other means whose object is a greater momentary swing of the balancer, actuated by the crank bar 31. Both kinds of means are provided for and arranged on the 40 tractor, shown in detail in Figures 3 and 4. This tractor comprises the following general parts:

(A) The two wheel axles 45 and 46 on which the inwardly flanged wheels 45a and 45b, 46a 45 and 46b are fixedly mounted.

(B) The chassis, 47, a skeleton frame, advantageously formed of angles, channel irons and plates and supported on the bearings 45c and 46c in which the wheel axles run.

About midway between the axles, the center post, 30, is mounted, to be described in detail later, and furthermore the chassis supports the other members of the tractor, viz.

(C) The motor, 48, preferably an electric 60 motor, although other locomotive means may be substituted, as pointed out before,

(D) The gear train 49, actuated from the rear axle, which lifts the center post but also has a controlling element, 50, activating parts E and F, 65

(E) The gear train 51, comprising the motor drive and the drive of the crank bar, 31, and finally

(F) The cam-controlled shift mechanism 52, for lifting the gear train 51. This part acts as 70 intermediary between D and E.

The construction of the framework forming the chassis, may be seen from Figures 3 and 4, and need not be discussed further, as it can be varied considerably.

The center post, 30, consists of a stationary guiding-channel, 30a, which is firmly held between the channels 55, forming part of the chassis, and can further be braced in any convenient way by struts or braces from the chassis frame, as indicated at 56, see Figures 3 and 4. In this channel is guided the bar, 30b, to the top of which the center of the balancer is pivotally connected at 33 (Fig. 1). Cross ties 30c at suitable heights confine the bar 30b within the guidance of the channel 30a. At the base, the bar 30b is cushioned on the compression spring 57.

The motor, 48, is hung from the platform, 44, and can be of any suitable type, back geared, or provided with special speed reduction means, if necessary.

It drives the worm, 58, which in turn drives the worm gear, 59, keyed on the front axle, 45. Loosely mounted on the same axle, are two lever arms, 60a and 60b, in which is journaled a shaft, 61. This shaft, together with the arms, forms a U-shaped yoke, which can be swung around the front axle. On the shaft, 61, is keyed a gear, 62, driven by a pinion, 63, fixedly mounted on the front axle. The ratio of this gear train is 1:2, so that the gear 62 makes one revolution to every two of the front axle. At one place the shaft 61 is "cranked", i. e. it has an eccentric portion, 64, which passes through a slot, 65, in the pitman or sweep-arm 66.

This pitman is a lever, pivoted loosely upon the front axle, like the yoke levers 60a and 60b, and at its free end is jointed to the crankbar 31 which controls the balancer. The slotted portion has a removable cap, 66a, forming one side of the slot, 65, and it is evident that when the eccentric shaft portion turns within the slot, the pitman is thereby caused to oscillate in a vertical direction, and that the stroke at the free end is larger than the eccentricity of the shaft in the proportion of the distances of the free end and of the eccentric respectively from the front axle. The eccentricity and this proportion is so calculated that the resulting oscillation of the balancer is of the required magnitude, as defined before. How this "trotting" oscillation within a small angle is eventually and temporarily increased, will be described later on, but may for the present be left aside.

The rear axle, 46, actuates another gear train, 49, consisting of the two large gears, 68 and 70, keyed on shafts 79 and 78 respectively, and the intermediate pinions, 67 and 69, the former on axle 46, the latter on shaft 79. The gear ratios are a matter of option, but in the illustrated example, they are chosen as 1:3 both times, and therefore gear 70 makes one revolution to nine of the rear axle.

On the disk of gear 70 are mounted at the same radial distance from the center, two gear segments, 71 and 72, which therefore form the equivalent of a separate "mutilated" gear or cam. These geared segments intermittently engage another mutilated pinion, 73a, which is blended together and partly integral with another mutilated gear, 73b, in such a fashion that they may have the same hub and disk but that their teeth are of different pitch diameter and lie in different planes. This bastard-gear, as it may be called, is mounted on a shaft, 74, journaled in separate stands, 75, and is arranged adjacent to the center post 30. The geared segment, 73b, is adapted to engage the

rack, 76, adjustably mounted on the face of the bar 30b. From the directions of the arrows it will become evident that the bastard gear, when it is temporarily rotated, will lift the bar 30b a certain height, and when its teeth are released, permit it to drop back upon the spring, 57. It is to be remarked in this connection that the segment 71 occupies about 40°, and the opposite segment 72 about 80° of the face area of the gear. The latter segment however is not toothed throughout but only for the same peripheral distance as the former. The rest is made up by a cam portion, generated by increasing the lateral thickness of the last tooth of segment 72—so to speak—until it covers nearly 40°.

The action of the mutilated gear segments then will be as follows: We will assume that two revolutions of the wheels, mounted on the rear (or front) axle represent one alternation of movement of the horse, i. e. one complete oscillation of the balancer, the ratio of the crank wheel 62 to 63 being 2:1. Then one complete turn of the gear 70 and the segments mounted thereon, represents 4½ alternations or 9 phases. As long as no teeth of these segments are engaged, the bastard gear keeps at rest in the position shown.

When segment 71 engages segment 73a of the bastard gear, segment 73b of the latter begins to lift the rack and therewith the bar 30b. This continues until the last tooth of 71 shown in the Figure 3 on the right corner, sets the last tooth of 73a, shown on the left corner, free again. Then the weight of the center bar and everything supported thereby, causes the bastard gear to snap back again into the position shown, and the shock of the falling bar is diminished by the bumper spring 57. The lifting of the center bar therefore occurs within an angle which corresponds to one phase, that is, half an alternation of movement, 40°, being the ninth part of 360°. When after three more phases (120°), the segment 72 engages the bastard gear, it lifts the bar during one phase and keeps it suspended during the next phase, as the last tooth of 73a does not disengage until it has passed the cam portion 77, generated from the last tooth of 72, as before described. The dropping of the center-bar is therefore delayed for the rest of the alternation. A little rubber bumper, 73c, fastened to the stationary channel, 30a, prevents the bastard gear from swinging too far back, when released by the gear segments 71 or 77.

On the shaft 78 is also mounted a spur gear 80 which engages another spur gear 81 of double its pitch diameter. The latter therefore revolves once in 18 phases, or 9 alternations, and is loosely mounted on shaft 79. Collars, 82a and 82b, keep it in alignment with the gear 80. On the face of 81 is adjustably fastened by bolts, 84, running in concentric slots, 83, the cam 50. A forked lever, 86, is pivotally fastened to a bell crank, 87, with one end, and rides on the shaft, 79, with the other forked end. It carries a roller, 88, mounted laterally to its shank, and this roller rides on the cam, 50. A spring, 85, fastened to the forked end of the lever, 86, and to a suitable stationary point on the chassis frame, tends to urge the roller always towards the center of the cam. The lever 86 is pivoted to the bell crank 87 which is keyed on a shaft 87b, stationed separately across the frame work, and together with another keyed link 87a controls the shaft 61 as will be described.

This link 87a (see Fig. 4) is a one-armed lever, cooperating with the bell-crank 87, to equalize the lift of shaft 61 and spur-gear 62.

From the drawings it will be evident that 5 when the cam revolves, it pushes the roller, and therewith the forked lever, outwardly at various intervals and to variable distances, the roller automatically returning in the direction of the cam center. This motion oscillates the bell 10 crank 87, which is provided with another forked end, 89, engaging the shaft, 61, of the aforedescribed yoke, 60a and 60b. It therefore follows that the yoke with the gears and the oscillating pitman it carries, will be periodically 15 raised and lowered by the bell crank, which in turn is controlled by the fork lever, 86, and the cam, 50.

A detailed view of the shape of the cam is given in a diagram, Fig. 8, showing the 18 20 phases, positive and negative, i. e. the up-and-down swing of the balancer during one revolution of this cam on the inner circle. When the roller reaches a point on the outer circle A, and this coincides with a positive phase, the head-end of the balancer reaches its highest point; 25 i. e. the horse rears on its hind legs; when the roller reaches or travels on the circle B, and this coincides with a negative phase, the tail-end of the balancer reaches its highest point, i. e. the horse kicks with the hind legs. While 30 the roller travels on circle D, the balancer swings only within a small angle, corresponding to a regular trotting motion. The cam turns in the direction indicated by arrow C, while the roller travels on the cam in the direction of arrow R. The resulting sequence of motions is therefore: rearing, 3 phases of trotting, rearing, kicking, 3 phases of trotting, kicking, 3 phases of trotting, kicking, rearing, 3 phases of trotting 35 and the same cycle of motions once again. As will be observed, this shows a certain degree of irregularity and unexpected variation, imitating the whims of a bucking broncho.

There is one more mechanical feature of the 40 activation of the legs to be described. As was explained before, the alternating movement of the legs was effected by the change of the position of the balancer, and the depending arms, 34 and 35 in relation to the cross piece, 42, which 45 is held stationary.

As will be observed, the crosspiece, 42, is a T-like lateral extension of the depending arm of the bell crank, 90, (see Figure 5) which swings around the center, 33, of the balancer. As long 50 as the bar, 30b, does not rise, the lower end of the bell crank rests with the roller, 93, in the pit of the fork-shaped guide-rail, 94, fastened to the back of channel, 30a, and the crosspiece 55 42 is therefore held stationary. But when the bar is raised by the bastard gear, 73a, 73b, and the rack, 76, the bell crank together with the crosspiece, is lifted out of the pit, and can swing to either side. This is effected by either of the studs, 91 or 92, fastened to the side of the balancer, 32. As long as the balancer swings only within the smaller angle corresponding to the trotting motion, these studs do not contact with the bell crank, but with an increase of the 60 angle, and simultaneous lift of the bar and the vertical arm of the bell crank, the studs take the arm 90a along with them, and prevent an excess of deviation from the balancer.—This 65 swings the vertical arm with roller, 93, either 70 way, the latter following the contour of the 75

roller-guide-rail, 94. Thus the spread of the legs cannot exceed the maximum spread in the trotting motion.

Of the mechanical features causing movements of the horse's body, it remains to describe the device which actuates the motion of the head. In a similar way as the legs are fixedly attached to the solid cross-shafts, 36a and 37a, and by means of a segmental ball race (43a, 43b) can oscillate within the body portion around a pivotal point, 36, or 37, the head is fixedly attached to a cross-shaft, 95, journaled on the balancer, 32, and is provided with two corresponding segmental ball race courses, 96, indicated in Figure 5, which are rotatably jointed to the main body. Keyed on the shaft, 95 is a lever, 97, and this lever is pivotally connected to the plunger or crank-bar, 31, at some suitable point by the link 98. Obviously, when the plunger moves up or down, and thereby changes its angularity with the balancer, 32, the lever, 97, and therewith the head, is oscillated up and down in the manner indicated by the different positions of the head in Figs. 1, 5 and 6.

It is to be noted that, if desired, the lengths 20 of the actuating levers, such as, 38, 38a, 39, 39a, 40, 40a, 41, 41a, or 97 and 98, can be made adjustable by running their connecting pivot-pins, such as for instance the one, connecting link 38 to 38a, or 40 to 40a, in slots, instead of round 30 holes, and modifying these pins in an analogous manner as the shafts 36 and 37 are modified, i. e. using a solid pin with a little sleeve on, each separately connected to the respective lever arms to insure independent movements. As 35 these adjustable slotted lever connections are however well known to those skilled in the art, a special illustration in detail has been dispensed with.

Special provision has furthermore been made 40 to prevent any accidental forward or backward tilting over of the horse and carriage which may result in a derailment. This, in the case that an electrical motor is provided on the carriage and the current is supplied from a third or conductor rail—which is the manner preferred by the inventor—can be accomplished in a simple way. As Figure 1 and Figure 9 suggest, a conductor rail, 100, is supported by insulator stands, 101, in a well known manner, and from the extreme ends of the carriage frame depend two sub-contact shoe holders, 102a and 102b, which are mounted in a resilient manner, i. e. they can give or take whatever play in the distance between the conductor rail and the carriage may be caused by the jolts of the moving tractor.

The contact shoe may be a plain friction shoe, as is common for electrical vehicles or, as shown, a roller shoe, 103, which usually provides enough contact area for a moderate current without causing excessive sparking.—This roller is rotatably journaled on the bent over lower end of a plunger, 104, the upper end of which is provided with a piston, 105, resiliently cushioned upon a spring, 106, within the cylinder, 107, fixedly supported by the carriage frame.

A little pin, 108, through the piston, which may be guided by a lateral slot in the cylinder (not shown), prevents the rotation of the plunger around its vertical axis, and thereby the dislocation of the contact roller. The play of the plunger is limited between the screw plug, 109, and the compressive spring, 106, and the provision of two sub-contactors, 102a and 102b, serves a double purpose. At eventual track 70 75

crossings, where it is necessary to interrupt the conductor rails by an under-soil bridge conduit, they keep the motor supplied with current, while either one of the contactors passes the rail gap—
5 a very common expedient in such cases—and besides the sub-contact rollers form safety anchors that prevent the lifting of either end of the carriage from the rail.

The motor may be driven by direct current, as
10 is assumed in the wiring diagram, Figure 10, or may be arranged for alternating current.

As the motor, 48, is started, or stopped, by a hand lever switch, 110, on the rider's saddle, it is necessary to employ an automatically actuated
15 rheostat, 111, as indicated in the wiring diagram, Figure 10. This rheostat may be mounted on the truck, or underneath it, in any convenient way, and its form or detail, does not enter into the claims of the invention.

20 Shortly described, the current, when the switch is closed, goes through the solenoid, 112, and thereby raises the plunger, 118, which closes a double branch circuit. One branch "m", which becomes the main lead for the motor circuit, 25 passes from the negative (third) rail through the resistance, 114, to the motor and, after passing the same, through an earth circuit via tractor axles, wheels and wheel rails, back to the generator; the other branch "n" goes through the 30 solenoid, 115, raises the plunger, 119, which is cushioned in a pneumatic dashpot, 116, and passes to the positive ground connection. This plunger, at its lower end, carries a bridge contact, 117, and when it rises, cuts thereby the resistance of the motor circuit gradually out.

35 The layout of the track system is otherwise optional, and will depend upon local conditions. The tracks may eventually cross each other, as said before. A platform, or station, from which the several horses may start, or to which they return, can be installed, a master switch, by which the current supply to the third rail system may be cut off, and other safety devices, can be provided.—It is also understood that the passengers can be safeguarded by being strapped to the saddles, and so forth.

40 A great many modifications and changes are possible within the rightful scope of the invention without deviating from the principle of the same. For instance, it would fall entirely within the scope of my invention, if the figure of another animal, f. i. an elephant, a bull, a jack-ass, or an imaginary animal, were substituted for the horse; or even if—omitting the levers actuating
45 the oscillating motions of the legs and head of the horse—the remaining mechanism were utilized for driving the figure of a boat, or an imitation of an airplane.

50 The utilization of the device for advertising purposes or the execution of the invention in miniature, as a toy, would also be a legitimate scope of my sought for patent protection.

55 In all cases where the rider might not be a human being, the starting and stopping of the carriage, of course, is not controlled from the saddle, or any other part of the horse itself, but by the main switch of the electrical current. But such changes are well understood and easily applied by persons skilled in the pertaining art.

70 The drawings therefore are to be taken as illustrative, not as restrictive, and the scope of the invention should be judged not so much by what the details reveal, but by the attached claims.

I claim:

1. A device, comprising a mechanical horse, means to produce a forward motion of the horse, means to simultaneously oscillate its body about a pivotal point, so as to imitate the trotting motion of a live horse, and means to periodically tilt the body about said point at a greater angle, so as to imitate the rearing and kicking motions of a horse.

10 2. A device, comprising a mechanical animal, means to produce a forward motion of the same, automatic means operatively connected with the aforesaid means to move the animal's legs, in imitation of the natural leg motions of an animal, and similar means to move the animal's head, in synchronism with the movements of its legs.

15 3. An amusement device, comprising a mechanical horse, balanced and pivoted above the ground on an upright supporting bar, means to oscillate its body about the pivotal point, imitating thereby the rocking motions of a trotting horse, means to periodically tilt the body about said point, at a greater angle, so as to imitate the rearing and the kicking motions of a horse, 20 and automatic means, to temporarily raise the supporting bar with the horse an adequate height, during the last named motions, so that the feet of the horse touch the ground.

25 4. An amusement device, comprising a mechanical horse, balanced and pivoted above ground on an upright supporting bar, means to oscillate its body about the pivotal point, imitating thereby the rocking motions of a trotting horse, automatic means to move the legs in synchronism with the oscillations, so as to imitate the ground on an upright supporting bar, means to periodically tilt the body about said point at a greater angle, so as to imitate the rearing and the kicking motions of a horse, and automatic 30 means to temporarily raise the supporting bar with the horse an adequate height during the last named motions, so that the feet of the horse touch the ground.

35 5. An amusement device, comprising a mechanical horse, balanced and pivoted above ground on an upright supporting bar, means to oscillate its body about the pivotal point, imitating thereby the rocking motions of a trotting horse, automatic means to move the legs and the head in synchronism with the oscillations, so as to imitate the motions of a trotting horse, means to periodically tilt the body about said point at a greater angle, so as to imitate the rearing and kicking motions of a horse, and automatic means to temporarily raise the supporting bar with the horse an adequate height during the last named 40 motions, so that the feet of the horse touch the ground.

45 6. An amusement device, comprising a me- 50

chanical horse, balanced and pivoted above ground on an upright supporting bar, means to oscillate its body about the pivotal point, imitating thereby the rocking motions of a trotting horse, automatic means to move the legs and the head in synchronism with the oscillations, so as to imitate the motions of a trotting horse, means to periodically tilt the body about said point at a greater angle, so as to imitate the rearing and kicking motions of a horse, and automatic means to temporarily raise the supporting bar with the horse an adequate height during the last named 55 motions, so that the feet of the horse touch the ground.

60 7. An amusement device, comprising a me- 65

chanically operated contrivance, adapted to carry a live rider, said contrivance pivotally oscillating on an upright supporting bar, the latter being supported upon a carriage, motive means to propel said carriage, automatic means operatively connected with said motive means to oscillate the contrivance about the pivotal point at a moderate angle, and automatic means, to periodically tilt the contrivance, forwardly and backwardly, about the pivotal point, at a greater angle.

70 8. An amusement device, comprising a me- 75

chanically operated contrivance, adapted to carry a live rider, said contrivance pivotally balanced above the ground on an upright support.

- ing bar, the latter being supported below the ground upon a carriage, motive means to propel said carriage, automatic means operatively connected with said motive means, to oscillate the contrivance about the pivotal balancing point at a moderate angle, and automatic means to periodically tilt the contrivance, forwardly and backwardly, about the pivotal point at a greater angle, and automatic means to temporarily raise the supporting bar with the contrivance an adequate height for this greater angle, so that the lowest portion of the rider-carrying contrivance touches the ground during the greater oscillations.
8. An amusement device, comprising a mechanically operated figure of a four-legged animal, adapted to carry a rider, said figure pivotally balanced above ground on an upright supporting bar, a carriage, located below ground on which said supporting bar is mounted, motive means to propel said carriage below ground, automatic means, operatively connected with said motive means to oscillate the animal's body about the pivotal balancing point at a moderate angle, to imitate thereby the rocking motions of a trotting animal, automatic means to move the legs in synchronism with the oscillations, to imitate the trotting motions of a live animal, means to periodically tilt the body of the figure at a greater angle, so as to imitate rearing and kicking motions of an animal, and means to temporarily raise the supporting bar with the animal an adequate height above ground, for the last named motions, so that its feet touch the ground during the greater oscillations.
9. The combination with an artificial horse, provided with a head and feet, pivotally jointed, so as to be capable of separate movements in relation to the main body, an upright standard upon which the horse is pivotally balanced, and a carriage, upon which said standard is mounted; of a motor, supported on, and adapted to propel said carriage, and a mechanism, likewise supported, said mechanism co-operatively connected to said motor, and adapted to actuate the body, the head and the feet of said artificial horse separately, so as to imitate the movements of a "bucking" broncho.
10. The combination with an artificial horse, provided with limbs pivotally jointed, so as to be capable of separate movements in relation to the main body, and a carriage upon which said horse is mounted; of motive means adapted to propel said carriage, a mechanism, supported on the carriage, and adapted to actuate the main body of the horse and its limbs separately, so as to imitate the movements of a "bucking" broncho, and guiding means, adapted to control said mechanism, in such a way, that a predetermined cycle of various movements of the horse is effected.
11. An amusement device, comprising a carriage, a supporting bar mounted on said carriage, a mechanical horse, pivotally balanced upon said bar, said horse having limbs, movable independently from the motion of the body, a plunger, co-operatively connected to the body of said horse, and adapted to impart an oscillating motion to it, links interconnected between the limbs and the supporting bar in such a way, as to impart separate motions to the former when the body is oscillated, automatic means, co-operatively interconnected between the carriage and the plunger, in such a manner that when the former is propelled, the lat-

ter is set into alternating motion and automatic means to control the amplitude of said alternating motion.

12. An amusement device, comprising a carriage, a supporting bar mounted on such carriage, a mechanical horse, pivotally balanced upon said bar, said horse having limbs, movable independently from the motion of the body, a plunger, co-operatively connected to the body of said horse, and adapted to impart an oscillating motion to it, links interconnected between the limbs and the supporting bar in such a way, as to impart separate motions to the former when the body is oscillated, automatic means, co-operatively interconnected between the carriage and the plunger in such a manner that when the former is propelled, the latter is set into alternating motion, automatic means to control the amplitude of said alternating motion, and means to limit the motion on the interconnecting links, so that the movement of the limbs does not become excessive.

13. An amusement device, comprising a carriage, a mechanical horse, pivotally balanced on an extensible upright standard, said horse having limbs pivotally jointed to the body, so as to be capable of movements, separate from those of the main body, and a motor-driven mechanism, provided on said carriage, comprising a gear train, a multiplicity of cams, actuated by said gear train, and a system of levers, cooperatively interconnecting said gear train and cams with the horse's limbs, said gear train and levers adapted thereby to produce oscillating motions of the horse's body and synchronously coordinated motions of the limbs, while the cams are adapted to so control the oscillating motions that they become periodically of varying amplitude and the upright standard is extended in proportion to the increase in amplitude substantially as described; the varying height of the horse's balancing position and variable motions of the limbs adapted to give an imitation of a bucking broncho.

14. An amusement device, comprising a carriage, a mechanical figure, representing an animal, pivotally balanced on a fixed support, and having its head and feet pivotally jointed to the body, so as to be capable of separate movements in relation to the main body, and a motor-driven mechanism, provided on said carriage, comprising a gear train, a multiplicity of cams, actuated by said gear train, and a system of levers, cooperatively interconnecting said gear train and cams with the animal's head and feet, said gear train and levers adapted thereby to produce oscillating motions of the animal's body and synchronously coordinated motions of the head and feet, while the cams are adapted to so control the oscillating motions that they become of varying amplitude, and automatic means, controlled by said cams, for initiating said varying amplitudes of the oscillations together with the coordinated motions of the head and feet after a predetermined cycle, so that said motions give an imitation of a capering animal substantially as shown and described.

15. An amusement device, comprising a carriage, a mechanical figure, representing an animal, balanced on a fixed support on said carriage and having its head and feet pivotally jointed to its main body, so as to be capable of separate movements in relation to its body, and a motor-driven mechanism, provided on said

carriage, comprising a gear train and a system of levers, cooperatively interconnecting said gear train with the animal's main body as well as with its head and feet, and designed to produce an oscillating motion of the main body and synchronously coordinated motions of the head and feet, said motions adapted to give an imitation of the forward movements of said animal.

16. An amusement device, comprising a carriage, a mechanical figure, representing an animal, balanced on a fixed support on said carriage and having its head and feet pivotally jointed to its main body, so as to be capable

of separate movements in relation to its body, and a motor-driven mechanism provided on said carriage, comprising a gear train, cams actuated by said gear train and a system of levers, cooperatively interconnecting said gear train and cams with the animal's main body as well as with its head and feet, and designed to produce oscillating motions of varying amplitude of the animal's body and synchronously coordinated motions of its head and feet, said motions adapted to give an imitation of a capering animal. 5
